(57) **CLAIM**

The ornamental design for an invisible setting for gemstones and diamonds, as shown and described.

DESCRIPTION

The FIGURE is a perspective view of an invisible setting for gemstones and diamonds. The surface(s) or portion(s) of the article not shown in the drawing or described in the specification form(s) no part of the claimed design. The portions of the article shown in broken lines are for illustrative purposes only and form no part of the claimed design.
